UNITED STATES PATENT OFFICE.

LOUIS V. BARACH, OF PITTSBURGH, PENNSYLVANIA.

GAME APPLIANCE.

Application filed May 11, 1923. Serial No. 638,431.

To all whom it may concern:

Be it known that I, LOUIS V. BARACH, a citizen of the United States, residing at Pittsburgh, in the county of Allegheny and State of Pennsylvania, have invented certain new and useful Improvements in Game Appliances, of which the following is a specification.

This invention relates to improvements in game appliances, more particularly ten pins and bowling balls, and although the invention is primarily designed to provide an improved construction for ten pins and bowling balls, it is to be understood that the construction can be employed for setting up any type of game appliance for which it is found to be applicable.

Important objects of the invention are to provide a game appliance construction of the class stated, which comprises a composite body embodying an inner hollow element of inexpensive material the thickness of which may be varied to give regulation weight to the appliance, and which includes an outer element of more expensive molded material of suitable configuration to provide an appliance of conventional form, under such conditions effecting a construction for the manufacture of highly efficient appliances at a minimum cost.

Further objects of the invention are to provide appliances of the character described, in a manner as hereinafter set forth, which is simple in its construction and arrangement, strong, durable and efficient in its use, attractive in appearance, and comparatively inexpensive to manufacture.

With the foregoing and other objects in view, the invention consists of the novel construction, combination and arrangement of parts herein specifically described, and illustrated in the accompanying drawings wherein are shown embodiment of the invention, but it is to be understood that changes, variations, and modifications can be resorted to which come within the scope of the claims hereunto appended.

In the drawing wherein like reference characters denote corresponding parts:—

Figure 1 is a vertical sectional view of a ten pin constructed in accordance with our invention.

Figure 2 is a sectional view of a bowling ball similarly constructed.

Referring in detail to the drawings, there

is shown in Figure 2 a bowling ball constructed in accordance with my invention, and comprising a composite body consisting of an inner spherical hollow member 1 and an outer spherical member 2.

The inner member is preferably constructed from aluminum, but may also be made from any other suitable metallic material. The outer member 2 is preferably constructed from micarta, but may also be made from other suitable composition materials susceptible of being molded to the inner member 1 and to the configuration desired and required.

As the material used in the construction of the outer member 2 is very costly as compared with the material used in the construction of the inner member 1, the former is made only of a thickness to give it sufficient strength to withstand the severe service to which it is necessarily subjected in use, while the thickness of the latter may be varied to give the ball the regulation weight required.

In the process of manufacture the micarta member 2 is fixedly molded to the inner metal member 1, and such combination of the two members 1 and 2 provides a composite unit compatible with the conventional kindred appliances.

The periphery of the molded member 2 is formed with the usual suitably disposed finger holes 3, the walls of which are preferably engrafted, as illustrated, to facilitate the accurate manipulation of the ball by the player.

The ten pin illustrated in Figure 1, of the drawings, is constructed in a manner identical to that described relative to the bowling ball hereinbefore, with the exception of its configuration which is of the conventional form of a ten pin.

The ten pin consists of a hollow inner metal section 4 completely enclosed by the outer section 5 which latter is constructed from any suitable composition material susceptible to being molded, preferably micarta.

The enlarged lower portion of the outer member 5 is formed with a peripheral recess 6, adapted for the reception of a resilient collar (not shown) of rubber or its equivalent, which latter is provided for absorbing the shock when the ten pin is impacted by the bowling ball. The ten pin is

formed with the usual flat lower end 7 to maintain it in the upright position when set up.

It will here be noted that while our improved construction of game appliance is illustrated and described as adapted to bowling balls and ten pins, the construction may be successfully embodied in the manufacture of divers game appliances.

10 In the manufacture of my improved game appliances the inner spherical hollow metal member 1, of the bowling ball, and the hollow inner metal section 4, of the ten pin, are preferably constructed with roughed outer surfaces for the purpose of augmenting the adherent properties of respective inner and outer members in combining them as a composite unit.

What I claim is:—

20 1. A game appliance comprising a composite body portion consisting of a hollow inner section formed throughout of metallic material and with the material at the outer

periphery of said section roughened, and an outer section of non-metallic material completely enclosing said inner section and directly adhering to said roughened periphery, said roughened periphery of said inner section augmenting the adherent properties of said sections, said outer section formed with a pair of finger holes each having the wall thereof engrafted throughout and its bottom spaced from the outer periphery of the inner section.

2. A game appliance comprising a composite body portion consisting of a hollow inner section formed throughout of aluminum and with the aluminum at the outer periphery of said section roughened, and an outer section of micarta completely enclosing said inner section and directly adhering to said roughened periphery, said roughened periphery of each section augmenting the adherent properties of said sections.

In testimony whereof I affix my signature.
LOUIS V. BARACH.
